UNITED STATES PATENT OFFICE.

HENRY D. JONES, OF ASHTABULA, OHIO.

PARING-KNIFE ATTACHMENT.

1,099,052.

Specification of Letters Patent.

Patented June 2, 1914.

Application filed May 7, 1912. Serial No. 695,699.

To all whom it may concern:

Be it known that I, HENRY D. JONES, a citizen of the United States, residing at Ashtabula, in the county of Ashtabula and State of Ohio, have invented new and useful Improvements in Paring-Knife Attachments, of which the following is a specification.

The general object of this invention is 10 the provision of a finger rest particularly adapted for use in connection with paring knives, said rest being adapted to be applied to the knife in such a manner that the same will extend over the inner portion of the 15 blade adjacent the handle, whereby the operator's fingers will be prevented from coming in contact with said blade, thus eliminating the danger of cutting or otherwise hurting the fingers.

20 In carrying out the objects of the invention generally stated above, it will be understood, of course, that the essential features thereof are susceptible to changes in details and structural arrangements, preferred and 25 practical embodiments being shown in the accompanying drawing, wherein:—

Figure 1 is a side elevation of the invention applied to a knife, the hand of an operator being shown in dotted lines. Fig. 2 30 is a perspective view of a modified form of a finger guard.

Referring more particularly to the accompanying drawing in which like reference characters designate similar parts, 35 indicates the handle of a paring knife to which is secured the blade 6 of the ordinary well known construction. The handle 5 may be provided adjacent its inner end with an annular groove for a purpose which will 40 be presently described.

The attachment which comprises the essential feature of this invention consists of a single piece of resilient metal which is curved

longitudinally of its entire length to provide finger rest portion 9 which when in position is adapted to extend longitudinally of the back of the blade 6 and engage the same whereby the operator's fingers will be prevented from coming into contact with the back of the blade and thus prevent cutting 45 or otherwise hurting the fingers as is commonly the case with paring knives now in use. The inner end of the portion 9 is provided with a pair of laterally extending oppositely disposed wings 10 which are bent 50 inwardly as indicated at 11, whereby the said wings may be spaced only a slight distance apart.

From the foregoing description taken in connection with the drawing, it will be obvious that the invention contemplates providing a finger rest for paring knives which is simple in construction thus reducing the cost of manufacture of the same to a minimum and which is durable and effective 60 in carrying out the purpose for which it is designed.

What is claimed is:—

As an article of manufacture, an attachment comprising a channeled plate, and resilient fingers formed at one end of the plate, the said fingers projecting from the longitudinal edges of the plate at the channeled side thereof and being bent to provide convergent inner portions and parallel outer 75 portions, the said outer portions being arranged in proximity to each other and are adapted to frictionally engage opposite sides of a knife blade.

In testimony whereof I affix my signature 80 in presence of two witnesses.

HENRY D. JONES.
